US0D1077736S

(12) **United States Design Patent** (10) **Patent No.:** **US D1,077,736 S**
(45) **Date of Patent:** **** Jun. 3, 2025**

(54) **CHARGER**

(71) Applicant: **NINGBO UCOME LIGHTING CO., LTD.**, Ningbo (CN)

(72) Inventor: **Zeke Zhang**, Ningbo (CN)

(73) Assignee: **NINGBO UCOME LIGHTING CO., LTD.**, Ningbo (CN)

(**) Term: **15 Years**

(21) Appl. No.: **29/885,207**

(22) Filed: **Feb. 22, 2023**

(30) **Foreign Application Priority Data**

Sep. 14, 2022 (CN) 202230604948.3

(57) **CLAIM**

The ornamental design for a charger, as shown and described.

DESCRIPTION

FIG. 1 is a first perspective view of a charger showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

(Continued)

FIG. 9 is an enlarged view of the selected portion 9 in FIG. 2.

The broken lines shown in the drawings depict portions of the charger that form no part of the claimed design.

1 Claim, 9 Drawing Sheets
